United States Patent Office

Des. 229,924

Patented Jan. 15, 1974

229,924

BUILDING

C. Douglas Brown, P.O. Box 1579,
Panama City, Fla. 32401

Filed Dec. 11, 1970, Ser. No. 26,411

Term of patent 14 years

Int. Cl. D25—03

U.S. Cl. D13—1 F

FIG. 1

FIG. 2

FIG. 3

FIG. 4

FIG. 1 is a front elevational view of a building embodying my new design;

FIG. 2 is a side elevational view of the building as viewed 120° (degrees) to the right of the building as seen in FIG. 1;

FIG. 3 is a side elevational view of the building as viewed 120° (degrees) to the left of the building as seen in FIG. 1;

FIG. 4 is a plan view of the building with arrows A, B and C indicating the directions at which the views of FIGS. 1, 2 and 3 have been taken respectively.

I claim:

The ornamental design for a building, substantially as shown.
